UNITED STATES PATENT OFFICE.

ELLIOTT G. THORP, OF BOSTON, MASSACHUSETTS.

DESIGN FOR A BOOK OR ALBUM LEAF.

SPECIFICATION forming part of **Design No. 20,166**, dated **September 23, 1890**.

Application filed May 6, 1890. Serial No. 350,801. Term of patent $3\frac{1}{2}$ years.

To all whom it may concern:

Be it known that I, ELLIOTT G. THORP, of Boston, county of Suffolk, and State of Massachusetts, have invented and produced a new and original Design for Book or Album Leaves, of which the following is a specification, reference being had to the accompanying drawings, forming part thereof.

In the drawings, Figure 1 shows a leaf embodying my design, and Fig. 2 shows two leaves as bound together.

The leading feature of my design consists in a leaf for a book or album having a semi-circular contour or outline and an opening or openings for pictures within the outline.

Referring by letter to the drawings, A designates a leaf having a straight edge a , which may be the binding-edge, and the curved edge a' . The curve a' extends from one end of the edge a to the other end thereof. 20

The ordinary picture space or spaces a^2 may be provided, as shown.

What I claim is—

The design for an album-leaf, substantially as shown and described.
